UNITED STATES PATENT OFFICE

144,375

DESIGN FOR HARD-SURFACED FLOOR COVERING

Robert V. Garner, Westwood, and Angelo P. Macchi, Walpole, Mass., assignors to Bird & Son, Inc., East Walpole, Mass., a corporation of Massachusetts

Application November 16, 1945, Serial No. 123,831

Term of patent 7 years

(Cl. D92—4)

To all whom it may concern:

Be it known that we, Robert V. Garner and Angelo P. Macchi, citizens of the United States, residing, respectively, at Westwood and Walpole, in the county of Norfolk and Commonwealth of Massachusetts, have invented a new, original, and ornamental Design for a Hard-Surfaced Floor Covering, of which the following is a specification, reference being had to the accompanying drawing, forming a part thereof.

The figure of the drawing is a plan view of a piece of floor covering embodying our new design, the basic unit of the design being subject to such repetition as may be necessary to cover any given floor area or desired portion thereof.

We claim:

The ornamental design for hard-surfaced floor covering, as shown and described.

ROBERT V. GARNER.
ANGELO P. MACCHI.
